GRAIN CAR DOOR.

APPLICATION FILED DEC. 27, 1915.

Patented May 16, 1916.

3 SHEETS—SHEET 3.

UNITED STATES PATENT OFFICE.

JOSEPH TONY, OF LEAVENWORTH, KANSAS, ASSIGNOR OF ONE-THIRD TO JOHN E. MUNSEY, OF LEAVENWORTH, KANSAS.

GRAIN-CAR DOOR.

1,163,254.

Specification of Letters Patent. Patented May 16, 1916.

Application filed December 27, 1915. Serial No. 68,877.

To all whom it may concern:

Be it known that I, JOSEPH TONY, a citizen of the United States, residing at Leavenworth, in the county of Leavenworth and State of Kansas, have invented certain new and useful Improvements in Grain-Car Doors; and I do declare the following to be a full, clear, and exact description of the invention, such as will enable others skilled in the art to which it appertains to make and use the same.

My invention which relates to improvements in grain car doors has for its object to improve upon the general construction of devices of this class to such an extent as to provide a comparatively simple yet highly efficient door which may be easily operated.

With this general object in view, the invention resides in certain novel features of construction and in unique combinations of parts to be hereinafter fully described and claimed, the descriptive matter being supplemented by the accompanying drawings which constitute a part of this application and in which:

Figure 1 is an elevation of the inner face of one of the sides of a grain car with the improved door closed; Fig. 2 is a similar view with the door opened; Figs. 3 and 4 are vertical transverse sections taken on the planes designated respectively by the lines 3-3 of Fig. 1 and 4-4 of Fig. 2; Fig. 5 is an enlarged side elevation of the carriage plate and parts carried thereby, a portion of one of the latches mounted on said plate being shown in section; Figs. 6 and 7 are vertical transverse sections taken on the planes indicated by the lines 6-6 and 7-7 of Fig. 5; Fig. 8 is a horizontal sectional view as viewed on the plane indicated by the line 8-8 of Fig. 5; Fig. 9 is a detail longitudinal sectional view as seen on the plane indicated by the line 9-9 of Fig. 8; Fig. 10 is a perspective view of one of the drums which assists in raising the door, and the operating spring of said drum; and Fig. 11 is a detail horizontal sectional view taken on the plane indicated by the line 11-11 of Fig. 2.

In specifically describing the invention shown in the drawings above briefly described, similar reference characters will be placed on corresponding parts throughout the several views and reference will be here-
in made to the numerous elements by their
respective indices. To this end, S refers to
one of the upright sides of a common type
of grain car, said side having at its upper
edge the usual longitudinally disposed beam 60
B and being equipped with any preferred
type of door frame F. As is usual with cars
of this class, the beam B is disposed on the
interior thereof and serves as anchoring
means for the sheathing of the car.

Secured to the inner side of the beam B by any preferred means, is a pair of vertically spaced horizontal tracks 1, said tracks being spaced inwardly from the beam by washers or the like 2. The tracks 1 receive 70 therebetween a pair of grooved rollers 3 rotatably mounted on bolts or the like projecting rearwardly from an elongated horizontally disposed carriage plate 4, the flat sides of said plate being positioned in upright planes. Riveted or otherwise secured to the upper corners of the plate 4, is a pair of angular brackets or straps 5 through whose lower ends bolts 6 are passed horizontally, said bolts being also passed through the ends 80 of a horizontal shaft 7 spaced inwardly from the plate 4.

Mounted rotatably on the opposite ends of the shaft 7 and having inwardly extending hubs 8 received snugly in the opposite ends 85 of a tube 9 which surrounds said shaft, is a pair of peripherally grooved drums 10, the hubs of said drums being provided with eyes 11 confined within the tube 9 and receiving the outer hooked ends of a pair of coil 90 springs 12 also confined in said tube and encircling the shaft. The inner ends of the springs 12 are hooked into eyes 13 on a pair of collars 14 which are slidably keyed on the aforesaid shaft. Thus, when the drums 10 are rotated, the two springs 12 will be placed under tension, this being expedient for reasons to be hereinafter specified.

Partially wound on the drums 10 and depending therefrom, is a pair of cables 16 100

whose lower ends are connected to eyes 17 which are formed on the upper corners of the lower section 18 of the door, said section being in the form of a sheet metal plate 5 whose opposite ends are received slidably in upright angle-iron guides 19 when the door is closed, said guides being secured to the lower end of the frame F as shown. Hinged at its lower edge to the upper edge of the section 18 by any preferred style of hinges 20, is an upper door section 21 also in the form of a sheet metal plate, the section 21 being preferably of less length than the section 18.

15 The upper corners of the door section 21 are provided with laterally extending perforated ears 22 of appropriate formation contacting with other perforated ears 23 which extend laterally from the sides of the 20 frame F, bolts 24 being passed removably through the perforations in the ears 22 and 23 to hold the aforesaid section 21 against outward movement when the door is closed. However, when it is desired to open the 25 door, the bolts 24 are removed, thereby allowing the section 21 to fold inwardly and downwardly on the section 18. The tension of the springs 12 will now cause the cable 16 to be wound on the drums 10 as the door 30 is raised. For holding the door in raised position, the two latches 25 are provided, said latches being shown in the form of upright levers fulcrumed between their ends on the bolts 6 and having said ends offset 35 laterally, the lower ends of said levers being formed with hooks 26 adapted to engage notches 27 in the upright edges of the section 18, near the upper end of said edges. In order to effectively guide the section 18 and 40 thus insure that the hooks 26 properly engage the notches 27 and remain in engagement therewith as required, the levers 25 are provided with pairs of depending guide fingers 28 designed to receive the upper 45 corners of the section 18 therebetween and thus produce the results desired.

The upper ends of the levers 25 are pivoted to the outer ends of a pair of longitudinally disposed links 29 which are slideable through tubes 30 against the tension of springs 31 confined in said tubes, the inner ends of the links 29 being provided with eyes to which a pair of cables 32 are secured, said cables being extended from the eyes toward the center of the carriage plate 4 and being here passed over sheaves 33 and connected by a ring or the like 34. Thus, when a downward pull is exerted on said ring, the latching levers 25 will be so rocked as 60 to release the door to allow the latter to be lowered.

The carriage plate 4 is normally held in the position shown in Fig. 1 by a horizon-

tally swinging spring actuated latch 35 secured to the beam B and coöperating with 65 one of the brackets 5, but when this latch is released, after first raising the door as above explained, said plate and door may be moved longitudinally on the tracks 1 to the position shown in Fig. 2. To retain the carriage plate in this position, an additional latch 35^a identical in construction with the latch 35 is provided.

Preferably used in conjunction with the parts above described, is some type of guide 75 for receiving the lower edge of the door when opened, this guide being indicated in the present embodiment of the invention in the form of an angle metal bar 36.

A device of the class specified constructed 80 as above described, will be found to possess a number of advantageous characteristics and to be highly efficient in operation.

All parts are preferably manufactured as illustrated in the drawings, but if found 85 expedient, numerous changes may be made within the scope of the invention as claimed.

I claim:—

1. The combination with the upright side of a grain car having therein a door frame, of a horizontal track at the upper end of said frame and extending laterally therefrom, a carriage mounted on said track and of a length approximately equal to the width of the frame, upright guides at the 95 lower ends of the opposed sides of the frame, a door mounted in said guides for vertical movement therefrom, winding means on the carriage, cables depending from said means and connected to the door, 100 whereby the latter may be raised from its guides, and a horizontal guide beneath the laterally extending portion of the track to receive said door when the carriage is moved onto said portion of the track after first 105 raising the door.

2. The combination with the upright side of a grain car having therein a door frame, of a horizontal track at the upper end of said frame and extending laterally therefrom, a carriage mounted on said track and of a length substantially equal to the width of the frame, upright guides extending along the lower ends of the opposed sides of the frame, a lower door section mounted 115 in said guides for vertical movement therefrom, an upper door section hinged at its lower edge to the upper edge of said lower section and adapted to fold downwardly thereon, means for normally holding said 120 upper section in upright position, winding means on the carriage, cables depending from said winding means and connected to the lower door section whereby the entire door may be raised when the upper section 125 is released and folded upon the lower, and

a horizontal guide below the laterally extending portion of the track to receive the lower edges of both door sections when the carriage is moved onto said laterally extending portion after first raising the entire door.

In testimony whereof I have hereunto set

my hand in presence of two subscribing witnesses.

JOSEPH TONY.
